FOOTBALL GAMEBOARD

Craig J. Wilcockson, 385 Mason Ave.,
Staten Island, N.Y. 10305

Filed Dec. 9, 1974, Ser. No. 530,725

Int. Cl. D21—01

U.S. Cl. D34—5 FG

FIG. 3

FIG. 5

FIG. 6

FIG. 4

FIG. 1 is a side elevational view of a football gameboard embodying my design;

FIG. 2 is a left end view thereof;

FIG. 3 is a cross sectional view along line 3-3 of FIG. 1;

FIG. 4 is a right end view thereof;

FIG. 5 is a cross sectional view along line 5-5 of FIG. 1; and

FIG. 6 is a cross sectional view along line 6-6 of FIG. 1.

I claim:

The ornamental design for a football gameboard, substantially as shown.
